UNITED STATES PATENT OFFICE.

JOHN A. CAMP, OF PALMS, CALIFORNIA.

ADVERTISING DEVICE.

1,409,077.

Specification of Letters Patent. Patented Mar. 7, 1922.

Application filed January 24, 1921. Serial No. 439,516.

To all whom it may concern:

Be it known that I, JOHN A. CAMP, a citizen of the United States, and resident of Palms, in the county of Los Angeles and State of California, have invented new and useful Improvements in an Advertising Device, of which the following is a specification.

This invention relates to display apparatus, and has for its objects, first, the provision of a device of large capacity for intermittently and successively exhibiting panels having printed matter therein; second, to provide a mounting for the panels such that they may be changed; third, to provide novel actuating means for the panel carrier; and fourth, to provide details of structure whereby a simple, positively operated, and compact structure is obtained.

I obtain the above mentioned objects together with other objects and corresponding accomplishments by means of the embodiment of my invention illustrated in the accompanying drawing, in which:

Fig. 1 is a perspective view of a complete apparatus; Fig. 2 is a perspective on an enlarged scale of details of the actuating mechanism, the foundation plate being broken away to better show the mechanism; Fig. 3 is a perspective view of a fragment of the panel carrier, a panel arm and a fragment of a panel being shown; Fig. 4 is a vertical section through the device; Fig. 5 is an elevation of the drive shaft and panel carriers thereon, parts thereof being in section; Fig. 6 is a perspective view of a panel carrying disk; Fig. 7 is a perspective view of a locking disk; and Fig. 8 is an elevation of a panel frame which may be used instead of the arms shown in preceding views.

While the device is especially useful for advertising purposes, it may be employed to impart information, such, as for illustration, indicating streets on car routes or stations at which cars or trains may stop.

Referring more particularly to the drawing, a housing or casing is indicated by 9. The front thereof may be open or covered by a transparent medium, such as glass, so that the panels within the casing in position for display are visible. Suitably journaled in the box and extending the length thereof is a shaft 10 and fixed to the shaft are panel carrying disks 11. The disks are provided with apertures 12 preferably arranged in a circle and spaced from each other. These

apertures are designed to receive the ends of the panel carrying arms later described. Cooperating with each carrying disk is a locking guard comprising two disks 13 and 13'. Each locking disk has a notch 14. The locking disks are held in selected angular positions with respect to one another by a compression spring 15 mounted on the shaft intermediate the locking guards. In the construction shown herein bushings 16 are slidably mounted upon the shaft between the ends of the spring and the locking disks to cheapen the construction. Spring 15 presses the members of a pair of locking disks 70 against each other, their frictional resistance holding them in adjusted position.

Fixed upon the shaft 10 at one end thereof is a ratchet wheel 17. A base plate 18 serves as a foundation for carrying one journal of shaft 10 and the advancing mechanism. Mounted upon the base plate 18 is a block 19. A bracket plate 20 is secured to the block, and pivotally mounted between the plates is a lever 21 carrying at one end a pawl 22 for moving the ratchet wheel. A retractile spring 23 is secured to the lever 21 and to the base plate. Lever 21 forms the armature for an electromagnet 24 disposed so as to move the lever against the action of spring 23. The winding of electromagnet 24 is in circuit with a source of electrical energy and an interrupter 25. This interrupter may be mechanically, thermally, or otherwise operated so as to make and break the circuit at determined intervals. Upon energization of the electromagnet, lever 21 is moved causing pawl 22 to advance the ratchet wheel a step.

Mounted in the block 19 is an abutment screw 26 for limiting the retractile movement of lever 21. By adjustment of the screw 26, the magnitude of the steps advanced by the ratchet wheel will be regulated. Pivotally mounted in the other end of block 19 is a locking pawl 27 for preventing the ratchet wheel from being moved in the reverse direction.

Arms 28 are mounted upon the carrying disks, and panels secured to the arms. Referring to the arm shown in Fig. 3, it consists of a wire bent at right angles to itself at one end to form a pintle 29 and having an eye 30 at the other end. The arms are mounted upon the carrying disks by inserting the pintles in the apertures 12. As each arm is inserted in position the

notches 14 in a pair of locking disks are caused to register with each other, and the aperture receiving the pindle. After the arm is in position on the carrying disk, the 5 members of the pair of locking disks are then turned so, that the notches are out of registration with each other, thereby providing a guard which prevents accidental displacement of the arms from the carrying 10 disks. It will be noted that washers 31 may be employed to space the cooperating carrying disk and locking guard. The construction just described is such that single arms may conveniently be removed or 15 changed. Where it is intended that a set of arms be maintained and changed only as a set, a single locking disk without a notch may be employed. In this case the locking disk must be held away from the carrying 20 disk while changing the arms.

The panels are mounted upon the arms by passing fasteners 32 through the eyes 30 and corresponding apertures in the panel. The number of carrying disks and arms may 25 be varied. Herein I have shown two. The panels may be cut away as shown in Fig. 1 to accommodate them to the disks. In Fig. 8 a panel frame is shown consisting of a single piece of wire or the like with 30 arms having pintles 33 and 34 facing in the same direction. The panel is bordered by the frame. Only one guard is necessary, as by locking the pindle 34 to the carrying disks in the manner of pintles 29 35 at the right of Fig. 5, the frames are secured against displacement.

Mounted in the casing 9 at the top thereof is a gate 35 against which the panels may rest while being displayed in their upper 40 position. An opaque plate 36 may screen either the lower or upper panel in displayed position as desired, so that one only is visible. This is useful for certain purposes.

45 The device operates in the following manner:

The interrupter 25 intermittently energizes the electromagnet 24 causing it to advance the ratchet wheel step by step. This 50 causes an intermittent rotation of the shaft 10 and the disks 11, causing the arms 28 to be revolved, the latter pivoting upon their pintles. A panel attached to two corresponding arms will hang downwardly in 55 a vertical position displaying the matter imprinted on one side of the panel. As the panel moves backward, the succeeding panel drops from its upper vertical position in front of the lower panel displaying one side 60 of the succeeding panel to view. As the arms are carried inwardly they rest against the pindle of the following arm and are supported thereby eventually reaching a vertical position displaying the other side of 65 the panel. After passing the vertical posi-

tion, they drop downwardly turning about their pivot points on the carrying disks. If it is desired to hold the panels in their upper position, the gate 35 is used. Thus, the other sides of each panel will be progressively displayed. In this manner, each side of the panel is alternately displayed, one side in the upper position and the other side in the lower position. Due to the intermittent operation of the shaft 10, the panels are displayed for an interval of time in their stationary position.

The panels may be illuminated by lights 37 mounted upon the casing. If it is desired to screen one side of the panel, the opaque screen 36 may be disposed above or below the shaft 10 to cut off the vision of either the panels in their upper or lower positions. This is advantageous, where the device is used for indicating streets on a car route. Corresponding sides of the panels may have the street names arranged in one order, while the opposite sides may have the names arranged in the reverse order. Thus, when traveling in one direction, the opaque screen is arranged so that the sides of the panels having the streets in one order of progression are visible. Upon return of the car over the route, the screen 36 is moved to display the other side of the panels with 95 the series of streets in the reverse order. The screen is also useful when it is desired to use transparent panels, and illuminate them. Such panels can only be exhibited in either their upper or lower position. The length of time that a panel is displayed may be varied by using less carrying arms and less panels. For illustration, if four panels are used instead of twelve, the time that each panel would be displayed would be 100 three times greater. The use of locking disks makes it possible to vary the number of panels and interchange the panels. The set screw 26 also makes it possible to vary the time of exposure by varying the amount of 105 motion of the pawl and therefore of the ratchet wheel at each movement of the lever.

The gate 35 is not essential to the operation of the mechanism, but is useful to hold the panels at any desired angle or position 110 before they swing downwardly to make room for the next panel. It is obvious that any mechanical variations of the structure may be resorted to without departing from the spirit of the invention.

120 What I claim is:

1. A display device comprising the combination of rotative spaced carrying wheels, a series of display panels pivotally mounted to swing on said wheels, and guard plates 125 adjacent the points of connection of the panels with the wheels to retain the pivots on the carrying wheels.

2. A display device comprising the combination of rotative connected car- 130

rying wheels, a series of display panels pivotally mounted adjacent to the circumference of the wheels and extending parallel to the axis of the wheels, said panels being 5 detachably mounted on the wheels, and guard disks adjacent the points of connection of the panels with the wheels to retain the same against displacement on the carrying wheels.

10 3. A display device comprising the combination of a shaft suitably journalled, spaced carrying wheels mounted on said shaft, a series of display panels pivotally mounted on said wheels adjacent their circumferences by pintles extending parallel to the axis of the wheel, said pintles serving as supports for preceding panels; said panels being detachably mounted on the wheels, and disks secured on said shafts adjacent 15 the points of connection of the panels to the wheels to retain the panels on the wheels.

20 4. A display device comprising in combination rotative spaced carrying wheels, said wheels being provided with a plurality of holes near their circumferences, a plurality of display panels, a pair of pivots arranged respectively at opposite ends of each of said panels, one pivot extending inwardly 25 and the other pivot extending outwardly through a hole in said disks respectively, and a disk adjacent a wheel adapted to be held in fixed spaced relation for detachably 30 engaging the pivots in a wheel to hold the pivots in the holes of said wheel.

35 5. A display device comprising in combination rotative connected spaced carrying wheels, a series of display panels pivotally mounted adjacent to the circumference of the wheels and extending parallel to the axis of the latter, said panels being detachably mounted on the wheels, and a guard disk adjacent the points of connection of the panels with a wheel, mounted so to be 40 moved to and from said carrying wheels to retain the panels against displacement.

45 6. A display device comprising in com-

binatiion a shaft suitably journalled, spaced carrying wheels provided with a plurality of apertures near their circumferences mounted 50 on said shaft, a plurality of display panels, a pair of pintles arranged respectively at opposite ends of each of said panels for disposal in said apertures, guard disks slidably mounted on said shaft and resiliently pressed 55 toward said carrying wheels for detachably engaging said pintles to hold the latter in the apertures in said wheels.

60 7. A display device comprising in combination a shaft suitably journalled, spaced carrying wheels provided with a plurality of apertures near their circumferences mounted on said shaft, a plurality of display panels each having a pair of pintles at opposite ends extending outwardly, guard 65 disks slidably mounted on said shaft on the inner sides of said carrying wheels for detachably engaging said pintles to hold the latter in the apertures in said wheels, and a spring interposed between said guard disks 70 to resiliently press said guard disks toward said carrying wheels.

75 8. A display device including a shaft suitably journalled on a frame, a pair of spaced carrying wheels mounted on said shaft, a series of display panels pivotally mounted on said wheels adjacent their circumference and extending parallel to the axis of the wheels, the panels each being detachably mounted on the wheels, a disc 80 secured on said shaft adjacent the points of connection of the panels to the wheels to retain the panels on the wheels, means for advancing the wheels step by step, said means comprising an electromagnetically 85 actuated lever pivoted on the frame and having a pawl thereon adapted to engage a ratchet wheel fixed for rotation with one of the carrying wheels.

In witness that I claim the foregoing I 90 have hereunto subscribed my name this 6th day of January, 1921.

JOHN A. CAMP.
